SPARK PLUG

Rex J. L. Dutterer, Hastings, Mich., assignor to
Hastings Manufacturing Company, Hastings,
Mich.

Application June 24, 1946, Serial No. 678,829

5 Claims. (Cl. 123—169)

1

This invention relates to improvements in spark plug.

The principal objects of this invention are:

First, to provide a spark plug which may be manufactured to uniform specifications in mass production methods.

Second, to provide effective means for conducting heat away from the electrode of a spark plug.

Third, to provide a spark plug with both an efficient heat dissipating characteristic and a positive seal around the electrode.

Fourth, to provide an effective seal for the center electrode of a spark plug which may be applied without requiring a second cleaning process to remove excess sealing material.

Fifth, to provide a seal for the center electrode of a spark plug which is both effective and inexpensive.

The drawings, of which there is one sheet illustrate a preferred form of the invention.

Fig. 1 is a vertical cross-sectional view through a spark plug embodying the invention.

Fig. 2 is an enlarged fragmentary cross-sectional view showing the details of construction of the seal in the center of the spark plug.

In the drawings, the reference character 1 indicates a porcelain or ceramic insulator which is formed with a central bore 2 and the sloping exterior shouldered portion 3. The bore 2 is provided with a threaded section 4 near the middle thereof and a lower portion 5 of reduced cross-section.

The shouldered portion 3 of the insulator is arranged to fit within the sleeve member 6 and be sealed therein by folding over the rim 7 of the sleeve to clamp the gaskets 8 tightly against the shouldered portion. The sleeve 6 is provided with the usual hex nut shaped body 9 and threaded lower portion 10 for installing the spark plug in an engine. An external electrode 11 is secured to the sleeve 10.

The central bore 2 receives the upper electrode 12 which is threaded at 121 into the threaded portion 4 of the bore and is provided at its upper end with a shouldered terminal tip 13. The lower end of the electrode 12 is tapered as at 14 to fit within and engage the upper end of a coil spring 15. The lower end of the spring 15 rests upon the shoulder 16 of the lower electrode 17. The shoulder 16 rests upon the lower wall of the central bore at the upper end of the reduced portion 5. The spring is made of heat and corrosion resistant metal and gives a complete metallic path between the two electrodes.

2

A mixture of cement and finely divided metal powder is packed around the upper end of the lower electrode 17 as is indicated at 18. The metals to be used are preferably nickel, molybdenum, or copper and the purpose of the mixture is to increase the heat conductivity of the filler around the upper end of the lower electrode, and around the bottom of the coil spring 15. A predetermined rate of heat dissipation 10 may thus be assured in mass production of the plugs. This is desirable since the lower electrode 17 is subjected to the heat of the spark and the burning gases in the combustion chamber as well as the heating effect of the current passing 15 through it to cause the spark.

It will be noted that the mixture of cement and metal fills only about one half of the space between the upper and lower electrodes. The remaining space is filled as indicated at 19 with 20 a cement or ceramic mixture of non-electrical and low heat conducting capacity. The mixture is determined by the composition and expansion characteristics of the material forming the insulator 1 and is chosen to have the same coefficient of expansion as the insulator. The cement will thus form a tight seal between the upper electrode 12 and the walls of the bore 2 which will not be broken by unequal expansion of the cement and the insulator. It should be noted that the threaded portion 4 of the insulator extends below the end of the upper electrode so that the cement can effectively seal the bore by engagement with the threads.

The spark plug may be easily assembled by 35 inserting the first lower electrode 16, then the spring 15, and then the metal and cement mixture 18 in the central bore. The insulating cement 19 may then be added and the upper electrode 12 screwed into the threaded portion 40 4 of the bore. It should be noted that the spring 15 will maintain the lower electrode in a uniform position and will form an effective and continuous metal connection between the upper and lower electrodes for the passage of current there- 45 through.

The lower mixture of cement and metal serves to conduct heat away from the lower electrode as was explained before, and the upper section of cement will effectively seal the spark plug against the passage of gas along the center electrodes. The use of air or chemically setting cements eliminates the need for a heating process such as is used in the manufacture of some spark plugs.

55 Since the cement is introduced through the

bore 2 before the upper electrode 12 is installed and after the lower portion of the bore is closed by the lower electrode, there is little tendency for the cement to escape along the lower electrode and require that the spark plug be passed through a cleaning operation after assembly. The elimination of the cleaning and heating steps will materially reduce the cost of manufacture of the spark plug.

The invention has been illustrated and described in a highly satisfactory embodiment thereof. No attempt has been made to show other possible adaptations, as it is believed that this disclosure will enable those skilled in the art to adapt or embody the invention as may be desired.

Having thus described my invention, what I claim as new and desire to secure by Letters Patent is:

1. A spark plug comprising an insulating member having an enlarged exterior portion and defining a central bore having an internally threaded section intermediate of the ends thereof within said enlarged portion and a lower portion of reduced cross section spaced below said threaded portion, a lower electrode having a shoulder thereon intermediate of its ends, said lower electrode being positioned in said reduced section of said bore with its shoulder engaging the lower end of the upper portion of said bore, an upper electrode extending into said bore from the top thereof and having a threaded connection with the upper part of the threaded section of said bore, a coil spring positioned in said bore and extending between the shoulder of said lower electrode and the end of said upper electrode, a mixture of cement and powdered metal packed in said bore around the upper end of said lower electrode and a mixture of insulating cement positioned in said bore on top of said first mixture and filling the remainder of said bore to around the lower end of said upper electrode, said insulating cement having approximately the same coefficient of expansion as said insulating member.

2. A spark plug comprising an insulating member defining a central bore having a lower portion of reduced cross section, a lower electrode having a shoulder thereon intermediate of its ends, said lower electrode being positioned in said reduced section of said bore with its shoulder engaging the lower end of the upper portion of said bore, an upper electrode extending into said bore from the top thereof, a coil spring positioned in said bore and extending between the shoulder of said lower electrode and the end of said upper electrode, a mixture of cement and powdered metal packed in said bore around the upper end of said lower electrode and a mixture of insulating cement positioned in said bore on top of said first mixture and filling the remainder of said bore to around the lower end of said upper electrode, said insulating cement in its solidified state having approximately the same coefficient of expansion as said insulating member.

3. A spark plug comprising an insulating member defining a central bore having a lower portion of reduced cross section, a lower electrode positioned in said reduced section of said bore,

an upper electrode extending into said bore from the top thereof, and terminating above said lower electrode, a coil spring positioned in said bore and extending between said lower electrode and the end of said upper electrode, a mixture of cement and powdered metal positioned in said bore around the upper end of said lower electrode and a mixture of ceramic cement positioned in said bore on top of said first mixture and filling the remainder of said bore to around the lower end of said upper electrode, said ceramic cement in its solidified state having approximately the same coefficient of expansion as said insulating member.

4. The method of manufacturing a spark plug which comprises preparing an insulator with a central bore having a portion of reduced diameter at the bottom thereof, dropping a lower electrode into said bore so that said electrode projects through the bottom of said bore, dropping a metallic coil spring into said bore to rest upon said lower electrode, placing a predetermined amount of intermixed ceramic cement and finely divided metal into said bore and around the bottom of said coil spring and the top of said lower electrode, placing a predetermined amount of ceramic cement in said bore to rest upon the top of said intermixed cement and metal, and introducing an upper electrode into said bore until the lower end thereof penetrates said cement and contacts said spring, said uppermost cement in its solidified state having approximately the same coefficient of expansion as said insulator.

5. The method of manufacturing a spark plug which comprises preparing an insulator with a central bore having a portion of reduced diameter at the bottom thereof, and an internally threaded portion thereabove, dropping a lower electrode with a collar thereon into said bore so that said electrode projects through the bottom of said bore and said collar rests on the shoulder at the upper end of the reduced portion of said insulator, dropping a metallic coil spring into said bore to rest upon said lower electrode, placing a predetermined amount of intermixed ceramic cement and finely divided metal into said bore and around the bottom of said coil spring and the top of said lower electrode, placing a predetermined amount of ceramic cement in said bore to rest upon the top of said intermixed cement and metal, and screwing an upper electrode into said bore until the lower end thereof penetrates said cement and contacts said spring, said uppermost cement in its solidified state having approximately the same coefficient of expansion as said insulator.
